UNITED STATES PATENT OFFICE.

FRANK BURTON, OF DETROIT, MICHIGAN, ASSIGNOR TO ARTHUR E. FIXEL AND ALBERT ROSENFELD, TRUSTEES, BOTH OF DETROIT, MICHIGAN.

COIN-SELECTING DEVICE.

1,058,946.

Specification of Letters Patent.

Patented Apr. 15, 1913.

Application filed April 1, 1912. Serial No. 687,746.

To all whom it may concern:

Be it known that I, FRANK BURTON, a citizen of the United States, residing at Detroit, in the county of Wayne, State of Michigan, have invented certain new and useful Improvements in Coin-Selecting Devices; and I do declare the following to be a full, clear, and exact description of the invention, such as will enable others skilled in the art to which it appertains to make and use the same, reference being had to the accompanying drawings, and to the characters of reference marked thereon, which form a part of this specification.

This invention relates to a coin selecting device especially adapted for use in connection with telephone pay stations but adaptable for other purposes, and consists in the construction and arrangement of parts hereinafter more fully set forth and pointed out particularly in the claims.

The object of the invention is to provide simple and efficient means for gaging and selecting coins used in pay station telephones, and in coin controlled and coin actuated machines, whereby spurious coins will be allowed to either pass harmlessly through the device or will be arrested therein and discharged therefrom without becoming effective in actuating the mechanism.

The above object is attained by the construction illustrated in the accompanying drawings, in which:—

Figure 1 is a side elevation of one of the side plates which form the case into which the coins are introduced, and in which the calipers or gaging and selecting devices are located. Fig. 2 is a similar view showing in section a portion of the coin receiving box of a telephone pay station to which the coin selector is attached. Fig. 3 is a view similar to Fig. 2, showing how a coin larger than a nickel five cent piece will be arrested in the device and discharged therefrom. Fig. 4 is a transverse section through the complete case as on line 4—4 of Fig. 1. Fig. 5 is a horizontal section through the complete case as on line 5—5 of Fig. 1. Fig. 6 is a fragmentary view in horizontal section showing the spring returned shaft carrying a knurled disk through the medium of which said shaft may be actuated to swing the pivoted gage or caliper member.

Referring to the drawings by the characters of reference marked thereon, 1 and 2

designate the side pieces, respectively, which form the coin receiving case, the inner faces of which are provided with ribs or raised marginal portions 3, which, when said plates are placed together, co-operate to space the plates sufficiently to allow of the disposition of the operative parts therebetween and to afford gaging passages for the passage of the coins. At the top of said plates said co-operating ribs extend inwardly, as shown at 4, to form a centrally disposed gaging opening 5 communicating with the interior of the case. Said opening is in the form of a slot which is of such length and width as to admit of a coin but little larger in diameter and thickness than a nickel five cent piece. The gaging slot 5 communicates with a chamber 6 within the upper portion of the case into which a coin which is introduced into the opening 5 will fall. At the bottom of said chamber 6 is a gaging slot 7 formed by the walls of the side pieces of the case, the inwardly extending portions 8 of the dividing ribs, and the interposed blocks 9. This gaging slot 7 is of the exact length and width to correspond with the diameter and thickness of a nickel five cent piece so that should a nickel or a coin corresponding in size thereto be introduced into the case through the opening 5 it will pass through the gaging slot 7 into the lower chamber 10. Within said chamber 10, and pivoted at 11 between the side pieces 1 and 2 is a swinging caliper or gaging member 12 in the form of a bar or arm, which is provided with a slot 13, that, in length is somewhat less than the diameter of a nickel five cent piece. This swinging caliper or gaging member normally lies in a horizontal position within the chamber 10, and is adapted to swing in the arc of a circle upon the fulcrum or pivot 11 consisting of a shaft which projects at one side of the case and carries a knurled thumb wheel 14. Extending inwardly from said wheel is a hollow hub or sleeve 15 (see Fig. 6) which embraces the shaft 11 and forms a housing for the coil spring 16 which is wound about said shaft, and one end thereof is made fast to the side piece 1 of the case, while the other end is secured to the shaft by the transverse pin 17. By this arrangement the pivoted gaging member 12 may be swung upon its pivot by rotation of the thumb wheel, and when said wheel is released will be returned to its nor-

mal position by the action of the spring 16. The sides of the slotted opening 13 in the pivoted gaging member 12 are beveled, as shown at 18, to assist in directing a coin into said slot.

5 The parts are so disposed that a coin passing through the slot 7 will be directed into the slot 13 in the gaging member 12. If the coin be of the proper diameter it will lie in 10 said slot 13 in position to be discharged therefrom as the pivoted gaging member is actuated through a manipulation of the knurled wheel 14 hereinafter explained.

Pivoted in the outer end of the gaging 15 member 12 is a dog 19. This dog is provided with a tail piece 20, which, as the caliper or pivoted gaging member 12 is swung on its pivot, will engage the periphery of the coin lying in the slot 13 in said member. 20 At the free end of the dog 19 is a head piece 21, and between said head piece and the pivoted central portion of the dog is a notch 22. A stop pin 23 is mounted in the pivoted portion of the dog and adapted to engage the 25 end of the gaging member 12 to prevent the dog swinging upwardly out of position.

When a coin of the correct thickness and diameter is introduced into the case through the slot 5 it will pass through chamber 6 and 30 through the slot 7 into chamber 10, falling through said chamber 10 into the slot 13 in the pivoted member 12 wherein the coin will be arrested, as shown at 24 in Fig. 2. In this position of parts by a rotation of the knurled 35 wheel 14 the pivoted gaging member 12 may be swung upwardly in the arc of a circle, as shown by solid lines in Fig. 2. As said member is swung upon its pivot the dog 19 will swing on its fulcrum by gravity, so as 40 to cause the tail piece 20 thereof to bear against the periphery of the coin, as shown in said last mentioned figure. At the limit of the upward movement of the member 12 the block 9 will enter the notch 22 in the 45 dog and arrest its free end and cause it to swing farther on its pivot and carry the tail piece thereof forcibly against the coin, so as to eject the coin from the slot in the pivoted member 12, as shown by dotted lines in 50 Fig. 2.

This device is shown in connection with the coin box 25 of a telephone pay station which is provided with an aperture 26 in the wall thereof, over which the case is secured through the medium of the flanged 55 brackets 27 mounted on the sides thereof, so that upon a coin being discharged from the pivoted gaging member it falls into said box and may then be directed into a suitable 60 chute or guide, not shown, for any desired purpose.

Projecting at right angles from the pivoted gaging member 12 at the pivoted end thereof is a guard member 28 which normally occupies a vertical position, and serves

as a guard to prevent the possibility of a coin accidentally passing through the opening 26 into the box 25, after falling through the opening 7. Should a coin be deposited in the case too small in diameter, instead of 70 lodging in the pivoted gaging member 12 it will pass therethrough and fall from the case through the slotted opening 29 at the bottom thereof, as shown by dotted lines 30 in Fig. 1. After the coin has been discharged 75 from the pivoted gaging member by manipulation of the knurled wheel 14, as shown in Fig. 2, upon releasing said wheel the spring 16 will return the gaging member to its original horizontal position. When returning to said horizontal position the pivoted dog 19 will strike the lug 31 projecting from the wall of the case in the path thereof, and will be swung on its pivot so as to retract the tail piece 20 thereof and prevent it 80 projecting into the slot or passage 29 in a manner to afford an obstruction to the free 85 passage of a coin therethrough.

It will be noted on referring to Fig. 2 that as the pivoted gaging member is 80 swung upwardly the free end of the dog 19 will pass through the opening 7 and extend into the chamber 6. The purpose of this is to sweep from the chamber 6 a coin which might be lodged therein because of 85 the fact that it is too large in diameter to pass through the opening 7 as illustrated at 32 in Fig. 3, said coin in this operation, by reason of the engagement of the dog therewith, being discharged through the slotted 90 opening 33 in the rear edge of the case, as illustrated by dotted lines in said last mentioned figure.

Because of the fact that the pivoted coin 95 gage or caliper 12 is formed of a single piece through which the slot 13 of correct proportions passes, said gage is not liable to become ineffective for gaging coins because of wear through continual use, rendering the device 100 serviceable for an indefinite period. It will 110 further be noted that the sides of the case are formed of integral pieces wherein the various gaging slots or apertures are produced by milling said parts, enabling absolute 115 accuracy to be obtained in the dimensions thereof, and providing against variations with respect to said dimensions through wear or the improper disposition of movable parts.

Having thus fully set forth my invention, 120 What I claim as new and desire to secure by Letters Patent, is:—

1. In a coin selecting device, a case comprising side plates having integral gaging members formed thereon which coöperate 125 when said plates are placed together to form in conjunction with said plates caliper openings for testing coins, and manually actuatable means below one of said caliper openings and movable between said 130

plates for discharging from said case a coin of proper size.

2. In a coin testing device, a receiving case having a detention chamber in which 5 coins of large diameter are arrested, said chamber having an opening at the bottom through which coins of a given diameter may pass, and manually actuatable means movable through said opening for sweeping 10 from said chamber coins which have become arrested therein.

3. A coin testing device comprising a case, a detention chamber in which coins of relatively large diameter are arrested, a gaging 15 opening in the bottom of said case through which coins of a certain diameter may pass, a movable gaging member adapted to receive and retain coins of a certain diameter, and means for moving said gaging member to discharge a retained coin therefrom.

4. In a coin selecting device, a case having an opening in the top thereof for the introduction of coins, a chamber in said case 25 with which said opening communicates, a gaging opening in the bottom of said chamber through which coins of a certain diameter may pass, a second chamber below said gaging opening with which it communicates, 30 a swinging gaging member in said chamber having a gaging slot therein disposed to receive coins passing through said gaging opening, and means for actuating said swinging gaging member to discharge a contained coin therefrom.

5. A coin selecting device, comprising a case having an opening into which coins may be introduced, a movable gaging member having a gaging slot therein into which 40 coins introduced into the case are adapted to fall, a discharging dog pivoted in the end of said gaging member adapted to bear against the periphery of a coin therein, means for actuating said gaging member, 45 and a stop adapted to engage said dog and actuate it to eject the coin from the gaging member.

6. A coin selecting device, comprising a case into which a coin may be introduced, 50 a movable gaging member in said case, said member having a receiving slot adapted to retain coins of a certain diameter, means for moving said member to a position to discharge a coin therefrom, and an ejector carried by said gaging member and actuatable to eject a coin from the slot therein.

7. A coin selecting device, comprising a case formed of side plates, inwardly projecting coöperating members thereon form-

ing an opening for the passage of coins, a 60 gaging member pivoted between said plates, said member having a coin receiving and gaging slot therein, said gaging member normally lying in a horizontal position, and means for swinging said member upon a 65 pivot from a horizontal to a vertical position to discharge a retained coin from the gaging slot therein.

8. A coin selecting device, comprising a case having an opening therein for the introduction of coins, gaging means within 70 said case for directing coins of a certain diameter therethrough, a pivoted gaging member within said case adjacent the bottom thereof, said pivoted gaging member 75 having a gaging slot into which coins are directed, a box having a discharge opening adjacent said pivoted gaging member, and means for actuating said pivoted gaging member to discharge a retained coin through 80 said opening.

9. A coin selecting device, comprising a case having an opening therein for the introduction of coins, gaging means within 85 said case for directing coins of proper diameter therethrough, a pivoted gaging member within said case adjacent the bottom thereof, said pivoted gaging member having a gaging slot into which coins are directed, a receptacle having a discharge 90 opening adjacent said pivoted gaging member, means for actuating said pivoted gaging member to discharge a retained coin through said opening, and a movable guard 95 on the gaging member standing before said opening.

10. A coin selecting device, comprising a case having an opening therein for the introduction of coins, gaging means within 100 said case for directing coins of a certain diameter therethrough, a pivoted gaging member within said case adjacent the bottom thereof, said pivoted gaging member 105 having a gaging slot into which coins are directed, a receptacle having a discharge opening adjacent said pivoted gaging member, means for actuating said pivoted gaging member to discharge a retained coin through said opening, and means for returning the pivoted gaging member after 110 an actuation thereof.

In testimony whereof, I sign this specification in the presence of two witnesses.

FRANK BURTON.
